UNITED STATES PATENT OFFICE.

FLOYD B. KNISKERN, OF WILKINSBURG, PENNSYLVANIA, ASSIGNOR TO WESTINGHOUSE ELECTRIC & MANUFACTURING COMPANY, A CORPORATION OF PENNSYLVANIA.

INDICATING CLOSURE PLUG FOR CIRCUIT BREAKERS.

Application filed September 8, 1925. Serial No. 54,918.

- My invention relates to encased circuit interrupters and particularly to an indicating plug for the operating openings of the casings of such circuit interrupters.
- 5 One object of my invention is to provide a casing for an electrical device that shall give an external indication of the operative position of the enclosed device by the position of a plug inserted in the casing.
- 10 Another object of my invention is to provide an insertable plug for the casings for electrical apparatus, the position of which is dependent upon the operative position of the enclosed electrical device.
- 15 A further object of my invention is to provide a reversible plug for the casings of electrical apparatus of such form that the position in which it may be inserted in the casing at any time is dependent upon the 20 operative position of the enclosed apparatus.

In underground electrical distribution systems, circuit interrupters and the like are generally housed in water-proof casings. 25 In order to operate such devices, it is customary practice to remove a plug from the casing, insert a handle and operate the circuit interrupter to the desired position, after which the handle is removed and the 30 plug is re-inserted in the opening and screwed tight.

Unless a window is inserted in the casing, it is generally impossible to determine, from an external inspection, whether the 35 circuit interrupter is in its circuit opening or closing position. The use of indicating apparatus depending upon shafts or plungers passing through the walls of the casing is undesirable for the reason that it is 40 difficult to pack the joints and make them tight for long periods of time.

By my invention, I utilize a removable plug having different configurations at the 45 ends thereof to indicate the position of the circuit interrupter. The configurations conform to the positions of an indicating member of the circuit interrupter when it is in the circuit opening and closing positions. Accordingly, it is possible to insert 50 the plug into the casing only when the inward configuration corresponds to the position of a cooperating circuit interrupter element. The outer face of the plug always affords a visual indication of the position

of the circuit interrupter within the casing. 55

In the accompanying drawings,

Figure 1 is an elevational view of a circuit interrupter and casing particularly adapted for use in underground service embodying my invention;

Fig. 2 is a fragmentary view, partially in elevation and partially in section, of my improved indicating plug; and

Figs. 3 and 4 are elevational views of the ends of the indicating plug, showing the exposed configurations thereof when the circuit interrupter is in circuit-opening and circuit-closing positions, respectively.

Fig. 5 is a view, partially in elevation and partially in section, of a modified form of 70 my invention,

Figs. 6 and 7 are front and rear face views respectively, of an indicating plate embodying my invention, when the circuit interrupter is in the circuit closing position. 75

Figs. 8 and 9 are front and rear face views respectively, of an indicating plate embodying my invention, when the circuit interrupter is in the circuit opening position.

My invention comprises, in general, a water-tight casing 1 in which is mounted a circuit interrupter 2 of any preferred construction that comprises an operating arm 3 that cooperates with an indicating plug 4 inserted in the casing 1 for indicating the operative position of the circuit interrupter at any given time. 85

The casing 1 is of a type commonly utilized in subway construction wherein it is essential that the enclosed electrical apparatus shall be water-tight. The plug 4 is inserted in a threaded opening 5 in the casing 1 at a position adjacent to the operating arm 3. The operating arm 3 is mounted 90 on a shaft 6 that, in turn, carries an arm 7 terminating in a pin 8 that extends into the opening 5.

The plug 4 is provided with a groove 9 on one of its faces and a groove 11 of larger 100 diameter on its other face. The grooves 9 and 11 are adapted to afford clearance space for the pin 8 within the opening 5 when the plug 4 is in its water-tight position. Since the position of the pin 8 changes relatively 105 to the opening 5, with each actuation of the operating arm 3, the pin 8 is in position to enter the groove 9 of smaller diameter when

the circuit interrupter 2 is in its closed position, in which position, as is shown in Fig. 4, the legend "Closed" is exposed. When the circuit interrupter 2 is in its open position, the pin 8 is in position to enter the groove 11 of larger diameter, and, as is shown in Fig. 3, the legend "Open" is presented exteriorly of the casing 1.

Referring to Figs. 3 and 4, the legend "Open" is applied to the end of the plug 4 having the groove 9 of smaller diameter and the legend "Closed" is applied to the end of the plug 4 having the groove 11 of larger diameter. Accordingly, the legend exposed at any time is an indication of the condition or the operative position of the circuit interrupter, as is also the idle or exposed groove. Therefore, the legends refer to the condition of the circuit interrupter and not to the groove that should be inserted in the opening 5.

In the operation of a circuit interrupter embodying my invention, the casing 1 is clamped about the circuit interrupter 2 with the shaft 6 in juxtaposition to the opening 5. The shaft 6 is then moved to cause the operating rod 3 to move the circuit interrupter 2 into the desired circuit-controlling position. This may be done by inserting a handle through the opening 5 and engaging the arm 7, or the squared or slotted end of the shaft 6, as desired.

Regardless of the manner of imparting a turning movement to the shaft 6, the positions of the arm 7 and pin 8 correspond to the operative position of the circuit interrupter. After the handle has been withdrawn, the plug 4 is inserted in the opening 5 with the groove 9 or 11 that will coincide with the position of the pin 8 facing inwardly. The plug is then screwed into the casing 1 and the circuit interrupter is thereby rendered watertight. Should the pin 8 and the groove 9 or 11 fail to coincide, it will be impossible to screw the plug 4 into position, and the operator will receive warning that the circuit interrupter is not in the desired operating position.

When it is desired to change the operative position of the circuit interrupter, the plug 4 is removed, the shaft 6 is turned and, consequently, the position of the pin 8 relative to the opening 5 shifts correspondingly. The plug 4 is then turned end to end and screwed into the position relative to the pin 8 with the groove which had previously been idle and opening outwardly turned inwardly.

Since it is impossible to screw the plug 4 into its operative position, when the pin 8 and the groove 9 or 11 do not coincide, the operator always has a true visual indication of the operative position of the circuit interrupter by inspection of the exterior surface of the indicating plug 4.

Referring particularly to Figures 5 to 9 inclusive, I have shown a modified form of my invention in which a cover plate 21 for the opening 5 is screwed to the casing 1 by wing nuts 22 having threaded portions 23 for cooperation with threads in the casing. The wing nuts 22 pass through bosses 24 that terminate in a threaded portion 25 in order to avoid accidental separation of the cover plate 21 from the wing nuts 22 when they are removed from the casing 1. A crescent shaped lug 26 is formed on the rear or interior face of the plate 21, and the pin 8 is adapted to fit between the ends thereof.

The word "Closed" is printed on the outer face of the cover plate at the position opposite the ends of the lug 26 and the word "Open" is printed on the outer face of the cover plate at a point corresponding to the middle of the lug 26.

In the operation of this form of my invention, the circuit interrupter is manipulated with the result that the pin 8 is either in its upper or its lower position, as the case may be. The cover plate 21 is then placed over the opening 5 so that the pin 8 fits between the ends of the lugs 26. When the cover is so placed, the term "Open" or "Closed" will be in an upright position on the exterior of the casing 1, and will, accordingly, correctly indicate the condition of the circuit breaker. The wing nuts 22 are then drawn up and the casing 1 is rendered water-proof. With this form of my invention, it is impossible to screw the cover plate 21 down, when the relative position of the ends of the lugs 26 and the pin 8 is abnormal for the reason that the pin 8 will engage the lug 5 and prevent the threads of the wing nuts 22 from engaging the threads 105 in the casing 1.

It will thus be seen that I have devised a simple and accurate position indicator for enclosed electrical apparatus, which position indicator is free from rods or shafts 110 extending through the walls of the housing, and it also avoids the necessity for windows, peep holes and the like.

I do not wish to be restricted to the specific arrangement of parts herein set forth, 115 as various modifications thereof may be effected without departing from the spirit and scope of my invention. I desire, therefore, that only such limitations shall be imposed as are indicated in the appended claims.

I claim as my invention:

1. In combination, a movable member comprising an arm, a casing for the member having an opening disposed in cooperative relation to the arm, and a plug for the opening that is so constructed that its relative position in the opening is controlled by the position of the arm.

2. In combination, a member comprising an arm, a casing for the member having an

opening disposed in cooperative relation to the arm, and an indicating plug for the opening that is so constructed that its relative position in the opening is controlled by and is an indication of the position of the arm.

3. In combination, a member comprising an arm, a casing for the member having an opening disposed in cooperative relation to the arm, and a plug for the opening having a differently spaced indentation on each of its faces for cooperation with the arm in different positions thereof, whereby the exposed surface of the plug is an indication of the position of the arm.

4. In combination, a member comprising an arm, a casing for the member having an opening disposed in cooperative relation to the arm, and a plug for the opening having a differently spaced surface variation on each of its faces for cooperation with the arm in different positions thereof, whereby the exposed surface of the plug is an indication of the position of the arm.

25 5. In combination, a member comprising an arm, a casing for the member having an opening disposed in cooperative relation to the arm, and a plug for the opening having a differently spaced groove in each of its faces for cooperation with the arm in different positions thereof, whereby the spacing of the exposed groove is an indication of the position of the arm.

6. In combination, a member comprising an arm, a casing for the member having a threaded opening disposed in cooperative relation to the arm, and a threaded plug for the opening, the plug being provided with a differently spaced circular surface variation on each of its faces for cooperation with the arm in its different positions, whereby the surface configuration of the exposed end of the plug is an indication of the position of the arm.

45 7. In combination, a casing having an opening therein, a member within the casing comprising means extending before the opening and whose position relatively thereto varies with the operative condition of the member, and a reversible plug for the opening, the plug being of such form that its relative position in the opening is dependent upon the position of the said means.

50 8. In combination, a movable member, a

casing therefor having an opening, a member for insertion in said opening and cooperating with said movable member to indicate the position of the latter.

9. In combination, a movable member, a casing therefor having an opening, and a member for insertion in said opening, the position of said movable member determining the relation of the second named member whereby the latter indicates the position of the movable member.

10. In combination, a movable member having two positions, a casing for said member having an opening therein and a member for insertion in said opening in the one or the other of two relations corresponding respectively with said positions.

11. In combination, a switch member having two positions, a casing therefor having an opening, a member for insertion in said opening, said members having cooperating portions whereby the position of said switch member determines the manner of insertion of the second member to indicate said position.

12. In combination, a movable member, a casing therefor having an opening therein, and means for closing the opening coacting with said movable member to indicate the position of the latter.

13. In combination, a movable member, a casing therefor having an opening therein, and means for covering said opening, the position of said movable member determining the relation of the cover member whereby the latter indicates the position of the movable member.

14. In combination, a movable member having two positions, a casing for said member having an opening therein, and a member for covering the opening in the one or the other of two relations corresponding respectively with said positions.

15. In combination, a movable member having two positions, a casing for said member having an opening therein, and a cover plate for closing said opening in the one or the other of two relations corresponding respectively with said positions.

In testimony whereof, I have hereunto subscribed my name this first day of September, 1925.

FLOYD B. KNISKERN.
